(57) **CLAIM**

The ornamental design for a table/desk, as shown and described.

DESCRIPTION

FIG. 1 is a front perspective view of a table/desk showing our new design;

FIG. 2 is a rear perspective view thereof;

FIG. 3 is a front view thereof;

FIG. 4 is a rear view thereof;

FIG. 5 is a right side view, the left side view being a mirror image thereof;

FIG. 6 is a top view thereof;

FIG. 7 is a partial, enlarged top view thereof;

FIG. 8 is a front perspective view thereof, showing the top in an elevated position;

FIG. 9 is a front perspective view thereof, showing the top in an elevated position and extended forward; and,

FIG. 10 is a front perspective view thereof, showing the top in an elevated position and extended forward further than in FIG. 9.

The drawings include CAD lines that represent contour and not surface decoration.

The dashed broken lines illustrate structure that forms no part of the claimed design.

The dot-dash broken lines illustrate areas of enlargement; the dot-dash lines themselves form no part of the claimed design.
